United States Patent Office

Des. 205,749
Patented Sept. 13, 1966

205,749

TENT OR SIMILAR ARTICLE

Charles W. Moss, 5270 Geddes Road, Ann Arbor, Mich.

Filed June 30, 1965, Ser. No. 85,963

Term of patent 14 years

(Cl. D88—3)

FIG. 1

FIG. 2

FIG. 3

FIGURE 1 is a perspective view of a tent or similar article showing my new design;

I claim:

The ornamental design for a tent or similar article, substantially as shown.
